UNITED STATES PATENT OFFICE

CHRISTIAN CHRISTIANSEN, OF LYNN, MASSACHUSETTS, ASSIGNOR TO ROTARY MACHINE COMPANY, OF LYNN, MASSACHUSETTS, A CORPORATION OF MASSACHUSETTS

FOLDING MACHINE

Application filed April 11, 1928. Serial No. 269,201.

This invention relates to folding machines for folding and pressing down the edges of various kinds of material, and relates particularly to that type of machine shown and described in the application of Andrew R. Ridderstrom, Serial No. 77,593, filed December 24, 1925. The present invention is especially adapted for folding the edges of upper stock of footwear, as for instance for folding the edge of a binding strip previously stitched to the edge of the leather or other material for the shoe upper.

An object of the present invention is to provide an improved machine of the foregoing general type in which improved guiding means is provided and in which the folding may be carried out in an improved manner.

Other objects of this invention will appear in the following description and appended claims, reference being had to the drawings forming a part of this specification wherein like reference characters designate corresponding parts in the several views.

Fig. 1 is a side elevation, partly in section, of a machine embodying my invention.

Fig. 2 is an enlarged fragmentary detail view, partly in section, illustrating an embodiment of the invention.

Fig. 3 is in part a side elevation of the construction shown in Fig. 2.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways.

It is to be understood that the phraseology or terminology employed herein is for the purpose of description and not of limitation, and it is not intended to limit the invention beyond the terms of the several claims hereto appended or the requirements of the prior art.

For the purposes of illustration, I have shown my present invention as applied to a machine constructed in accordance with the above mentioned application of Andrew R.

Ridderstrom, Serial No. 77,593, although it will be understood that the invention may be carried out in various ways. The machine illustrated in Fig. 1 comprises in general a suitable base 20, to which is hinged an upper supporting frame 22 providing a housing for certain of the operating parts. Extending forwardly from the frame 22 is an overhanging arm 23 which is provided with an annular or oblique bore through which extends a rotary shaft 24. Secured to the rear end of the shaft 24 is a spiral gear 25 meshing with a spiral worm 26 carried at the forward end of a driving shaft 27 which is suitably journaled in the opposite side walls of the frame 22. This shaft may be driven by means of the belt wheel 28 through the medium of suitable clutch mechanism.

Secured to the shaft 24 is a rotatable head or upper roll 29. This rotary head is mounted on an axis extending at an angle transverse to the direction of feed. This head 29 carries a series of roller disks 30 which are mounted on short shafts (not shown) within the head 29 operated from the shaft 24. These disks 30 are preferably positively rotated in a direction opposite to the direction of rotation of the head 29 as indicated by the arrows. Each of the disks 30 is provided with an arcuate notch 31, and the arrangement of the disks 30 and the construction of the notches thereof are such that during operation the notches will straddle the folded edge of the material, as shown in Fig. 2, without flattening the French cord edge.

Beneath the rotary head 29 is mounted a work supporting roll 32 carried by a support 33, which in turn is mounted on a flexible shaft 34, this shaft being connected to the roll 32 so as to rotate the same during the feeding and folding operations. The shaft 34 has an extension 35 carrying a worm 36 operated from the shaft 27 by a worm shaft 37.

Extending through the front wall of the housing 22 is a shaft 38. This shaft carries a U-shaped spring arm 39. The outer end of the arm 39 is provided with an inclined guide 40 within which is slidingly mounted a retainer bar 41 controlled by means of a

spring 42. The lower end of this retainer bar 41 is bifurcated to provide outer and inner forks or arms 43 and 44. A retainer roll or disk 45 is rotatably mounted within the forks 43 and 44 on a journal pin 46. This retainer roller or disk cooperates with a projecting annular guide rib 47 formed on the lower work supporting roll 32, preferably in the manner shown in Fig. 2.

10 A further detailed description of the machine and operating parts shown in Fig. 1 is not deemed necessary herein, since this construction in the present instance is substantially the same as the machine illustrated in 15 the foregoing application, Serial No. 77,593, with the exception that a differently constructed work supporting roll 32 is provided, and a different type of plow 55 is provided.

10 Referring to Figs. 2 and 3, it will be noted 20 that the retainer bar 41, which carries the retainer roller 45, is provided with means for bending the leather 48 over the apex 47^a of the guide rib 47. In the present instance the fork or arm 44 of the retainer bar has an extension 44^a terminating at its lower end in a lip 49. This lip 49 is projected forwardly to provide a toe portion 50 adapted to engage the portion 48^a of the leather or other material which extends across and beyond the 25 guide rib and bend it downwardly over the guide rib 47 as the stock is fed under the retainer.

It will be noted that the inner face 49^a of the lip or projection 49 preferably extends 30 at substantially the same angle as the shorter face 47^c of the guide rib. The disk 45 is beveled at 45^c so that a space 51 is provided between the lower inner face of the retainer disk and the inner face of the lip or member 49. It will, therefore, be seen that the disk 45 and the projection 49 straddle opposite sides of the apex 47^a of the guide rib, and the guide projection 50, cooperating with the disk 45 act to bend or compress the leather 45 into slightly convex form or V-shape, thus holding the material upon the guide rib and forcing the relatively sharp apex 47^a of the guide rib into the stitch line 52, maintaining the stock in condition to keep the stitches 50 "smiling" or exposed. It will be understood that the binding strip 53 is stitched to the material or leather 48 by means of a line of stitching 52. The stitching is preferably loose, that is with a greater number of stitches 55 per inch than is customary in using other types of French cord machines. The galloon or binding strip is first opened out by hand by the operator before introducing the stock in the machine, and the loose stitching enables 60 the stitches to smile readily. The action of the members 50 and 45 in bending the leather over the guide rib result in keeping the stitches exposed and holding the rib on the stitch line. The projection 50 presses 65 into the leather as shown in Figs. 2 and 3

at and above the margin of the stitch line and assists in guiding the stock to the folding disks 30.

As in said prior Ridderstrom application the stock is simultaneously fed on the work supporting roll 32 by means of the overlapping disks 30 carried by the rotary head 29. These disks are located directly behind the retainer roll 45, and operate at an angle to the line of feed, as in said prior application. The disks 30 are given an orbital movement by means of the rotary head 29, and also have a positive rotary movement in the direction of the arrows in Fig. 2, opposite to the direction of rotation of the head 29, so that during the folding and feeding operation the notches 31 straddle and clear the rib 47.

It will be noted that the disks are each provided with a cam face 30^a commencing at the leading point 30^c of the notch 31 and terminating at 30^d, the remainder of the disk 30^b being a true circle. The pressing action of the disks is accomplished by the cam shaped edges 30^a. Due to the fact that these pressing faces or edges are not true circles or concentric with the edges 30^b, when the disks travel over the curved face of the roller 32 there will be a slight drag of the cam 30^a resulting in sufficient friction to pull the binding strip tightly around the edge of the leather. This action in conjunction with the straddling action of the notches 31 results in producing a round French cord.

From the foregoing it will be seen that the retainer disk 45 presses the material 48 against the face 47^b of the guide rib 47, and the projecting lip 50 forces the edge of the leather as well as the turned under portion of the binding strip against the face 47^c of the guide rib. As a result the apex 47^a of the guide rib will be held within the V-shaped space between the binding strip and the leather and will follow the stitch line so as to guide the stock. The member 49 is provided with a laterally extending bottom face 49^b and an end face 49^c which provide relatively narrow spaces or troughs between the faces 55^b and 55^a of the plow for the passage of the binding strip, thus guiding the binding strip to the folding and feeding disks.

What I claim is:

1. In a folding machine, a work support and retainer member for pressing the work against said support, said retainer member comprising a rotatable roll and means for guiding the edge of the work, and means for folding the work.

2. In a folding machine, a work support, a retainer member for pressing the work against said support, said member comprising a rotatable disk and a device for bending downwardly the edge of the work, and means for folding the work.

3. In a folding machine, a work support, a projecting guide engageable with the under

- side of the material, means for bending the edge of the material downwardly over said guide, and means for folding a binding strip around the edge of the material.
4. In a folding machine having fold pressing mechanism, a rotatable work supporting roll having an annular guide rib, a retainer comprising a rotatable disk for pressing the material against said rib and also comprising means for bending downwardly the edge of the material over said guide rib. 70
5. In a folding machine, a work support, a projecting guide engageable with the under side of the material, a member having a retainer disk or roll engaging the material at one side of said guide, and a device carried by said retainer for engaging the material at the opposite side of said guide. 75
6. In a folding machine, a work support having a projecting guide engageable with the under side of the material, a retainer comprising a pair of members for engaging the material at opposite sides of said guide thereby to hold the material in place with relation to the guide, and means for folding the work. 80
7. In a folding machine, a rotatable work supporting roll having an annular guide rib, a retainer for holding the material in position with relation to said guide rib during the feeding of the material, and comprising a rotatable disk for pressing the material against one side of the rib and a projecting member for bending the material downwardly at the opposite side of the rib, and means for folding the material. 85
8. In a folding machine for folding a binding strip stitched to a sheet of material, comprising a work support, a guide for guiding the material and strip at the stitch line, means for bending the edge of the material downwardly over said guide, and means for folding the binding strip. 90
9. In a folding machine, a work support having a projecting guide for guiding the material and binding strip at the stitch line, means for bending the edge of the material downwardly at one side of said guide, and means for folding the binding strip over the downwardly bent edge of the material. 95
10. In a folding machine, a work supporting roll having an annular guide rib for guiding the material and binding strip at the stitch line, a mounting carrying a retainer roll for pressing the material against said rib, means carried by said mounting for bending downwardly the edge of the material at one side of said rib, and means for folding the binding strip over said guide rib. 100
11. In a folding machine, a work supporting roll having an annular guide rib for guiding the material and binding strip at the stitch line, a mounting carrying a retainer roll for pressing the material against said rib, means carried by said mounting for bend- 105
- ing downwardly the edge of the material at one side of said rib, and a series of rotatable disks for folding the binding strip over said guide rib and pressing it against the work supporting roll at one side of the rib. 110
12. In a folding machine for folding a binding strip stitched to the edge of a material, comprising a lower work supporting roll having an annular guide rib adapted to guide the work at the stitch line, a retainer for pressing the material against one face of the guide rib, a retainer for pressing the material at the opposite side of the guide rib and means for folding the binding strip around the edge of the material. 115
13. In a folding machine for folding a binding strip stitched to the edge of a material, comprising a work support having a guide member adapted to project into the space between the material and binding strip for guiding the same along the stitch line, means for bending the material over said guide member, and means for folding the binding strip. 120
14. In a folding machine for folding a binding strip stitched to the edge of a material, comprising a work support having a guide member adapted to project into the space between the material and binding strip for guiding the same along the stitch line, means for bending the material over said guide member, and a series of overlapping rotatable disks having an orbital movement across the stitch line for feeding and folding the work. 125
15. In a folding machine for folding a binding strip stitched to the edge of a material, comprising a work support having a guide for guiding the work at the stitch line, a plow, a member for bending the material over said guide and also providing guide passages between itself and the plow for guiding the binding strip, and means for feeding the work. 130

In testimony whereof I affix my signature. CHRISTIAN CHRISTIANSEN.
